Des. 231,753
Patented June 4, 1974

231,753

RADIO RECEIVER

Tomio Fujiwara, Osaka, Japan, assignor to Matsushita
Electric Industrial Co., Ltd., Osaka, Japan

Filed Aug. 2, 1972, Ser. No. 277,197

Claims priority, application Japan Feb. 4, 1972

Term of patent 14 years

Int. Cl. D14—03

U.S. Cl. D56—4 B

FIG. 1

FIG. 2

FIG. 1 is top, right hand, front perspective view of a radio receiver showing my new design, with carrying strap extending from top of the radio receiver along the rear side of the same, partially hidden from view; and

FIG. 2 is a rear, left hand, bottom perspective view thereof, with the carrying strap extending from the top thereof downward adjacent the front thereof with an intermediate portion partially hidden from view.

I claim:

The ornamental design for a radio receiver, as shown and described.
